DESIGN FOR A TOY WAGON OR SIMILAR ARTICLE

Carl P. Sollmann, Montclair, N. J.

Application March 23, 1936, Serial No. 61,736

Term of patent 3½ years

To all whom it may concern:

Be it known that I, Carl P. Sollmann, a citizen of the United States of America, residing at Montclair, Essex County, State of New Jersey, have invented a new, original, and ornamental Design for a Toy Wagon or Similar Article, of which the following is a specification, reference being had to the accompanying drawing, forming a part thereof, wherein

Fig. 2 is a top view, and
Fig. 3 is a front view thereof.

I claim:

The ornamental design for a toy wagon or similar article substantially as shown.

In witness whereof, I have signed this application.

CARL P. SOLLMANN.
